BOTTOM RAIL FOR A ROLL-TYPE DOOR

Richard E. Smith, Columbus, Ohio, assignor to
Kinnear Corporation, Columbus, Ohio

Filed Sept. 11, 1969, Ser. No. 19,116

Term of patent 14 years

Int. Cl. D25—02

U.S. Cl. D13—1

FIG. 1 is a top-left perspective view of the bottom rail for a roll-type door embodying my design; and

FIG. 2 is a left-end elevational view of the bottom rail on an enlarged scale.

I claim:

The ornamental design for a bottom rail for a roll-type door, substantially as shown in full lines.
